UNITED STATES PATENT OFFICE.

EMIL HOLENSTEIN, OF BROOKLYN, NEW YORK, ASSIGNOR TO EDGAR C. HYMAN CO., OF NEW YORK, N. Y.

DESIGN FOR A SHAWL.

Application filed November 8, 1926. Serial No. 19,634. Term of patent 7 years.

To all whom it may concern:

Be it known that I, EMIL HOLENSTEIN, a citizen of Switzerland, residing in Brooklyn, county of Kings, and State of New York, have invented a new, original, and ornamental Design for Shawl, of which the following is a specification, reference being had to the accompanying drawing, forming part thereof.

The figure is a plan view of one fourth of the shawl showing my new design, the other corners being a mere repetition of this detail illustration.

I claim:

The ornamental design for a shawl substantially as shown and described.

EMIL HOLENSTEIN
